US0D1095245S

(12) United States Design Patent (10) Patent No.: US D1,095,245 S
(45) Date of Patent: * Sep. 30, 2025

(54) COOKIE PACKAGE

(71) Applicant: Intercontinental Great Brands LLC,
East Hanover, NJ (US)

(72) Inventors: Jeff Ferentz, Pine Brook, NJ (US);
Carol Corson, Pine Brook, NJ (US);
Dave Marsh, Pine Brook, NJ (US);
Tiffany London, Pine Brook, NJ (US);
Evan Stanhope, Pine Brook, NJ (US);
Jainette Quinones, East Hanover, NJ
(US); Sabrina Sierant, East Hanover,
NJ (US)

(73) Assignee: Intercontinental Great Brands LLC,
East Hanover, NJ (US)

() Term: 15 Years

(21) Appl. No.: 29/957,665

(22) Filed: Aug. 15, 2024

(51) LOC (15) Cl. 09-01
(52) U.S. Cl.
USPC D9/643; D9/434

(58) Field of Classification Search

USPC D9/504, 516, 520, 550, 552, 560, 600,

(57) CLAIM

The ornamental design for a cookie package as shown and described.

DESCRIPTION

FIG. 1 is a front view of a cookie package, showing our new design.

FIG. 2 is a rear view of the cookie package of FIG. 1.

FIG. 3 is a right side view of the cookie package of FIG. 1.

FIG. 4 is a left side view of the cookie package of FIG. 1.

FIG. 5 is a top view of the cookie package of FIG. 1.

FIG. 6 is a bottom view of the cookie package of FIG. 1. The dash-dot-dash lines depict the boundary of the claimed design and form no part of the claimed design. The dashed lines in the drawings depict portions of the cookie package that form no part of the claimed design. All of the unshaded areas within the dashed lines in the drawing depict portions of the cookie package that form no part of the claimed design.

1 Claim, 4 Drawing Sheets
